UNITED STATES PATENT OFFICE.

JOHN B. GOODWIN AND GEORGE GOODWIN, OF PROVIDENCE, RHODE ISLAND,
ASSIGNORS TO SAID GEORGE GOODWIN AND WILLIAM P. GOODWIN, OF
SAME PLACE.

FOLDING AND SWINGING GATE.

SPECIFICATION forming part of Letters Patent No. 381,066, dated April 10, 1888.

Application filed December 5, 1887. Serial No. 256,988. (No model.)

To all whom it may concern:

Be it known that we, JOHN B. GOODWIN and GEORGE GOODWIN, both of Providence, in the county of Providence and State of Rhode Island, have invented certain new and useful 5 Improvements in Folding and Swinging Gates, of which the following is a full, clear, and exact description, reference being had to the accompanying drawings, forming part of this specification.

Our invention relates to folding or collapsible gates or guards that are especially well adapted for use on steam railway-cars.

The objects of our invention are to simplify 15 the construction and operation of this class of gates and to render the same more efficient in their functions and neater in appearance.

To the aforesaid purposes our invention consists in the various constructions, arrangements, and combinations of the several parts 20 of the gate, as will be hereinafter fully described and claimed.

In order that our invention may be fully understood, we have illustrated in the accompanying drawings and will proceed to describe 25 the best forms thereof so far devised by us, with the knowledge that such forms admit of modifications, without, however, making a substantial departure from the spirit of the invention.

In the accompanying drawings, Figure 1 is a view of our improved gate, the cross-rods of which are in projected or extended position. The gate is here represented as mounted at one 30 side of a car-platform, the car being indicated in part. Fig. 2 is an enlarged partial view of the gate, showing in vertical section the casing which protects the spring which encircles the hinge-bar and is interposed between the 35 collar fixed under the upper hinge-sleeve and the next hinge-sleeve below. Fig. 3 is an enlarged sectional view taken on line 3 3 in Fig. 2. Fig. 4 is a sectional view taken on line 4 4 in Fig. 2. Fig. 5 is a central vertical sectional view of the foot of the hinge-bar with the surrounding hinge-sleeve which can only turn on the bar. Fig. 6 is an enlarged view of the bracket in which is adjustably mounted the head of the hinge-bar, as indicated in Fig. 1,

the bar being broken off in this view. Fig. 7 is a sectional view on line 7 7 in Fig. 6. Fig. 8 is an enlarged view of part of our improved gate, showing other detail forms of the sliding hinge-sleeves and the guiding means therefor. This view especially illustrates the means of locking the gate in folded position by virtue of the upper hinge sleeve having a set or locking screw, the dotted lines representing such sleeve as locked in its upward limit of movement. Fig. 9 is a sectional view on line 9 9 in Fig. 8. Fig. 10 is an enlarged view of a portion of another form of brace-bar than that shown in Fig. 1. Fig. 11 is a sectional view on line 11 11 in Fig. 8. Figs. 12, 13, 14, 15, 16, and 17 are enlarged views of parts of the gate, showing various details of construction respectively, as hereinafter fully described. Figs. 18, 19, and 20 are enlarged views, partly in section, of part of another form of hinge-bar with a sliding sleeve mounted thereon and with the operating lever (shown broken off) attached to such sleeve.

In the said drawings like numbers of reference designate corresponding parts throughout.

Referring to the drawings, the number 21 designates an ordinary steam railway-passenger car, part of the end, the platform, and hood of which only are shown. The tubular hinge-bar 22 is fixed at its foot by the plate 23, which is secured to the car-platform, and the angle or square head 24 of the bar is adjustably mounted in the slotted bracket 25, which is set upon the outside of the car-hood by means of the binding-screw 26, which is set in the end 20 of the hinge-bar and is formed with perforation 27, and which acts to bind upon the upper face of the bracket to hold the bar in any adjustment of its movement in the slot of the bracket, as will be understood from Figs. 6 and 7. The purpose of this horizontal adjustment of the upper end of the hinge-bar is to allow the hinge-bar to always be placed vertically, and as these car-hoods vary in the distances they overhang this variance may be 85 compensated for by such adjustment.

The lazy-tong gate 28 is composed of the cross-rods 29, which are pivoted to each other

and to the various parts of the structure by the pivot-studs 30. The gate is hinged to the hinge-bar by means of the hinge-sleeves 31, which are formed with the L-shaped guide-slots 32 for receiving the guide-pin 33, which is fixed in the hinge-bar 22, and which are provided with the horizontally-projecting guide-braces 34, having the horizontal slots 35 lying opposite each other in alignment, each sleeve having two such guide-braces extending parallel, as shown in Fig. 4.

In the slots 35 of the guide-braces work the pivot-studs 30 of the joints of the cross-rods 29, while others of the pivot-studs 30 are pivoted 15 to the solid portions of the braces 34 at points between the slots 35 and the body of the sleeve.

The guide-slot 32 of the lowest hinge-sleeve runs horizontally for about one-quarter the 20 circumference of the sleeve. The guide-pin 33 holds this sleeve from vertical movement, but permits it to perform a quarter-turn. As the gate is folded in toward the hinge-bar, all the sleeves except the lowest one will be forced 25 upward on the hinge-bar, and the pivot-studs 30, which work in the slots 35 of the guide-braces 34, will slide along the length of the slots. By this time the guide-pins 33 have reached the lower branch of the L-shaped slot 32, and the entire folded gate may then be 30 swung through the quadrant on the hinge-bar, in an evident manner, and the guide-pins 32 will serve to hold the gate collapsed while swung aside.

35 The sleeves 31 are limited in their downward movement by the collars 36, fixed upon the hinge-bar 22, as clearly indicated in Figs. 2 and 11; and hence these collars will act to prevent the gate from being projected beyond a 40 certain limit, since the sleeves must descend as the gate is extended or projected.

In the construction shown in Fig. 12 the sleeves below the two upper ones are held fast on the hinge-bar 22, which is rotatable, and in 45 the case of the non-sliding hinge-sleeves the guide-slot 35 of the guide-brace 34 has to be arranged vertically to allow the necessary upward movement of the guide-pin 30 working therein.

50 In Figs. 8, 9, 11, 16, 18, 19, and 20 we have shown other guiding means for the hinge-sleeves 31, the same consisting in a guide-rib, 37, fixed to the hinge-bar, and a guide-groove, 38, formed in the sleeve. This guide-groove 55 38 may run longitudinally of the sleeve, so that the sleeve may be slid over and clear of the rib, and may then be given a quarter-turn, and rest with its lower edge against the upper end of the rib, or the guide-groove 38 may be 60 L-shaped, as shown in Figs. 8 and 11, so that after the sleeve has been slid upward till the lower branch of the L-shaped groove comes to the upper end of the rib the sleeve may be given a quarter-turn, and the upper face of the 65 lower branch of the groove will rest upon the upper end of the guide-rib, and thus hold the sleeve in elevated position.

The brace-bar consists in an upper member, 39, and a lower member, 40, which are each formed with the vertical slots 41, and this two-part bar is pivoted vertically to the locking side of the gate by means of the pivot-studs 30 of the cross-rods working in the slots 41 of the brace-bar. The purpose of the transversely-divided brace-bar is to allow the same 70 to span over the hand-rail 42 on the car, so as to permit of the gate being projected in nearer to the car than would be the case with a one-piece brace-bar, which would strike the hand-rail and prevent the further extension of the 80 gate.

To the head of the brace-bar member 39 is pivoted the operating-lever 43, the other end of which is hinged to the brace or projection 34 on the upper hinge sleeve, 31, by means of 85 bolt 44, which is provided with a knob, 45, designed to be grasped and elevated by the operator in folding the gate. It will now be understood that as the knob 45 is elevated the operating-lever will be moved upward by the 90 end adjacent the knob, and all the hinge-sleeves will be slid upward, except the lowest one, which being held against vertical movement will cause the basal line of the gate to move in and out horizontally as the gate is 95 folded and projected. The brace-bar 39 40 will move in parallel with the hinge-bar, and the pivot-studs will slide in the slots 41. As the gate is folded, the same is increased in height, but of course cannot lengthen downwardly, because of the basal hinge-point being held stationary against vertical play.

The gate is held locked in projected position by means of one of the cross-rods 29 being formed with a latch head, 46, which snaps into 100 the latch-socket 47, formed on the under side of the brace or projection 34, formed on the upper hinge-sleeve, as shown in Figs. 1, 2, 3, and 8. To release the latch in folding the gate, the operator grasps the cross-rod having 110 the latch-head and moves it slightly out of the vertical plane, as will be understood from Fig. 3.

To assist the gate in the operations of extending the same and swinging it through the 115 quadrant when folded, we provide the spring 48, which encircles the hinge-bar, and which is normally under torsional tension when the gate is in extended position, as shown in Figs. 1 and 2. This spring is secured by its upper 120 end to the fixed collar 49, which is provided with the cam projection 50, over which the lower notched edge of the upper hinge-sleeve, 31, turns, the lower end of the spring being attached to the upper end of the turnable sleeve 125 31. The space between the fixed collar 49 and the subjacent sliding sleeve 31 is housed by the casing or shell 51, which is fixed to the collar 49 by the rivet 52, and the sleeve is adapted to move up and down and to turn 130 within the casing. As the gate is folded and the sleeve 31 slides up, the spring 48 is compressed against its fixed collar 49, and this tension of course tends to project or extend the

gate when left free to move into such position. When the gate is folded and is free to be swung aside through the quadrant, the torsional tension of the spring 48 comes into play and helps 5 to force the gate aside. In Fig. 15 we show this same construction of the coil-spring 48, the fixed collar 49, and the casing 51, which is cut away at 53 to allow the guide-brace 34 to swing through the quadrant when the gate is 10 folded and the sleeve 31 slides up in the casing. In this instance we do not support the hinge-bar from the car-hood, but shorten the bar and support it by the guard-rail 54 of the car-platform.

15 In Figs. 8 and 9 we show means for holding the upper hinge sleeve and its attached operating-lever 43 in locked position at the upward and downward limits of movement. This sleeve is provided with a set-screw, 54, which 20 is held in the perforation 55 in the sleeve of the pin 56, and the foot of the screw takes into the opening 57, formed in the hinge-bar, and thereby holds the sleeve locked in elevated position, as shown in broken lines in Fig. 8. 25 This screw may also serve to lock the gate when extended, by virtue of the eye 58, formed in the hinge-bar at the lowest limit of downward movement of the sleeve 31, as shown clearly in Fig. 9, which is a section on line 9-9 in Fig. 8. 30 In Fig. 10 the brace-bar 39 40 is shown with the horizontal extension 59, which projects inwardly toward the hinge-bar and is formed with the horizontal slot 60, in which slide the pivot-studs 30 of the cross-rods of the gate. 35 The outer end of the operating-lever 43 is hinged at 61 to this extension and has its inner end hinged to the brace 34, as shown in Fig. 8. This operating-lever in all the constructions shown forms a finishing-rail to the 40 top of the rods of the gate by covering the heads thereof when the gate is extended, as shown in several of the views, the cross-section of the lever being an inverted-U shape.

In the construction shown in Figs. 13 and 14 45 the upper hinge-sleeve, 31, has the guide-brace 34 formed with slot 35, in which slides the fixed stud 62, which is mounted on the operating-lever 43, the inner end of which is pivoted to the upright arm 63, formed on the turnable 50 sleeve 31, having the guide-groove 32 and pin 33. The lever 43 in this construction is not hinged to the vertical brace-bar at its outer end, but is only hinged at its inner end to the upright arm 63, and forms merely a finishing- 55 rail for the top of the gate when the latter is extended. The elevation of the lever does not effect the folding of the gate.

In Fig. 17 the hinge-sleeves are provided with slots 31, and are adapted to slide and turn 60 freely on the hinge-bar. The upper sleeve, however, has a horizontal slot, 32, and is held against vertical movement by the pin 33. The inner end of the lever 43 is provided with the horizontal slot 77, in which works the stud 30, 65 and the lever is also formed with a vertical slot or fork, 78, at its end, and the guide-brace 34 of the upper sleeve is also formed with a ver-

tical slot, 79, so that when the gate is folded the upper free end of the cross-rod 29 may move through the slots 78 and 79. 70

In Figs. 18, 19, and 20 we show a turnable hinge-bar, formed with two tubular sections. The upper section, 64, is provided with the clutch-face 65 on its lower edge, and is formed with a longitudinal slot, 66, through which projects the guide-pin 67, which is fixed on the core-piece 68, which extends through the center of both the sections. The lower section, 69, is formed with the clutch-face 70 on its upper edge, and is provided with a longitudinal 75 guide-rib, 37, over which slides the hinge-sleeve 31, as hereinbefore described. The upper section reciprocates on the core-piece 68, but does not turn thereon, while the lower section, 69, can be rotated when its clutch-face is disengaged from that of the upper section. 80

The upper section is held normally forced down by the spring 71, which is coiled about the core 68, which is secured to the stem 72, fixed to the car-hood 21. The lower end of the 90 spring bears upon the upper edge of the upper section, and the upper end of the spring bears against the stem 72. The casing 73 is fixed to the stem 72, and the upper section reciprocates therein. The lifting-pin 74 is fixed on the upper section, and is engaged by the L-shaped slot 32, formed in the sleeve 31, so that when the sleeve is raised from position in Fig. 18 to that in Fig. 19 the upper section will be raised out of engagement with the lower section, which 95 may then be turned through the quadrant, in an obvious manner. Fig. 20 shows a sectional hinge-bar, of a slightly different construction from that shown in Figs. 18 and 19. The upper section is attached to the core 68, and is 100 provided with a guide-pin, 67, which prevents rotation thereof, the guide-pin working in the slot 66, formed in the casing 73, which is fast upon the stem 72. The lifting-pin 74 is fixed on the core 68, instead of on the upper section, 105 and projects through the slot 75, formed in the lower section, 69. When the sleeve 31 is elevated into the dotted-line position, the lifting-pin will be raised, thereby lifting the core and moving the upper section out of engagement 110 with the lower and leaving the clutch 65 70 open, so that the lower section may rotate with the sleeve 31.

Having thus described our invention, we claim as new and desire to secure by Letters 115 Patent—

1. A lazy tong gate of the class described, having the hinging side thereof held at the basal point thereof against vertical movement, whereby the gate may be trussed and stayed 120 when extended, and whereby the basal line of the gate may be projected and folded on the horizontal, as described.

2. The combination, as hereinbefore set forth, with the hinge-bar, of a gate composed 125 of pivoted rods of the lazy-tong order, such gate having the hinging side thereof held stationary against vertical movement at the basal point thereof, and pivoted at one or more points 130

of such side to sliding members mounted loosely on the hinge-bar, as described.

3. The combination, as hereinbefore set forth, with the hinge-bar and the lazy-tong gate, of a set of sliding hinge-sleeves mounted on the hinge-bar and provided with lateral guide braces or lugs to which the several points of the gate are pivoted, substantially as and for the purpose herein described.

10 4. The combination, as hereinbefore set forth, with the hinge-bar and the lazy-tong gate, of the set of sliding hinge-sleeves mounted on the hinge-bar and provided with the guide-braces to which the gate is pivoted, the lowest 15 sleeve held against vertical movement and the other sleeves provided with stops to limit the downward movement thereof, substantially as described.

5. The combination, as hereinbefore set 20 forth, with the hinge bar and the lazy-tong gate, of the set of sliding hinge-sleeves mounted on the hinge-bar and provided with guide braces or lugs to which the gate is hinged by its respective points, such hinge-sleeves capable of sliding vertically and of turning in the 25 horizontal, and provided with guiding devices mounted on the hinge-bar, substantially as and for the purpose herein described.

6. The combination, as hereinbefore set 30 forth, with the hinge-bar and the lazy-tong gate, of the set of sliding and turning hinge-sleeves mounted on the hinge-bar and provided with slotted guide braces or lugs to which the several points of the gate are connected by hinge-pins sliding in the slots of the 35 guide-braces, substantially as described.

7. The combination, as hereinbefore set 40 forth, with the hinge-bar and the sliding hinge-sleeves mounted thereon and the lazy-tong gate having its rods pivoted to the guide-braces on such sleeves, of the vertical brace-bar located at the locking side of the gate and to which the rods of the gate are pivoted, the upper hinge-sleeve sliding on the hinge-bar, 45 and the operating-lever hinged intermediate the said upper hinge-sleeve and the vertical brace-bar, whereby the elevation and depression of the end of the operating-lever hinged to said sleeve may accordingly fold and project the gate, substantially as and for the purpose herein described.

8. The combination, as hereinbefore set 55 forth, with the hinge-bar and the sliding hinge-sleeves sliding thereon, the gate composed of pivoted rods of the lazy-tong order, of the upper sleeve sliding on the hinge-bar and having a projection or lug formed with a latch-socket, the upper end of one of the pivoted rods of the gate provided with a latch which 60 is adapted to lock in the latch-socket when the gate is extended, substantially as described.

9. The combination, as hereinbefore set 65 forth, with the hinge-bar and the lazy-tong gate, of the sliding hinge-sleeves mounted on the hinge-bar and provided with the lateral guide-braces, the L-shaped guide-slots formed in the sleeves, and the fixed guide-studs on the

hinge-bar taking through said slots, and the stops fixed on the hinge-bar to limit the downward movement of the sleeves, the rods of the 70 said gate pivoted to the guide-braces on the sleeves, substantially as and for the purpose herein described.

10. The combination, as hereinbefore set forth, with the hinge-bar, the sliding hinge-sleeves mounted thereon and provided with the guide-braces, and the lazy-tong gate pivoted to the said guide-braces, of the coil-spring encircling the hinge-bar and having one end thereof secured to one of the said hinge-sleeves, a fixed 80 collar on the hinge-bar, and the other end of said spring secured thereto, so as to hold the spring while the sleeve moves, substantially as described.

11. The combination, as hereinbefore set 85 forth, with the hinge-bar, the sliding hinge-sleeves mounted thereon and provided with the guide-braces, and the lazy-tong gate pivoted to the guide-braces, of the coil-spring encircling the hinge-bar and having one end thereof attached to one of the sleeves, a collar fixed to the hinge bar and the other end of the said spring secured thereto, and the casing fixed to the collar and receiving the end of the sleeve to which the spring is attached, substantially 90 as and for the purpose herein described.

12. The combination, as hereinbefore set forth, with the hinge-bar for the gate secured at its foot, of the bracket for receiving the head of the hinge-bar, which is adjustably 100 mounted in the bracket, substantially as described.

13. In a gate of the class described, the combination, with the hinge-bar for the gate, of a sliding sleeve mounted on the bar and connections intermediate the sleeve and the gate, a set-screw mounted on said sleeve, and a socket on the hinge-bar to receive the foot of said screw to lock the sleeve in fixed position thereon, substantially as and for the purpose 110 herein described.

14. The combination, as hereinbefore set forth, with the hinge-bar provided with the longitudinal guiding-ribs, of the sliding hinge-sleeves mounted on the hinge-bar and formed 115 with guide-grooves to receive the guide-ribs, substantially as described.

15. The combination, as hereinbefore set forth, with the lazy-tong gate, of the hinge-bar provided with guide-ribs, the sliding hinge-sleeves mounted on the hinge-bar and each formed with a longitudinal and a transverse guide-groove to receive the guide-ribs, the sleeves provided with guide-braces and the gate pivoted to such braces, the sleeves adapted 120 to slide over the guide-ribs and then to be turned on the hinge-bar, and the guide-ribs coacting with the transverse guide-grooves of the sleeves as stops against vertical descent of the sleeves when the sleeves are turned on 125 the hinge-bar, substantially as described.

16. The combination, with the hinge-bar and the lazy-tong gate hinged thereto, of the slotted vertical brace-bar pivoted to the lock-

- ing side of the gate and provided with a right-angled inwardly-projecting extension formed with a slot and a pivot-stud, the cross-rods of the gate working in said slot, a sliding hinge-sleeve mounted on the hinge-bar and provided with a lug or projection, and the operating-lever hinged by its respective ends to the extension on the brace-bar and the lug on the sleeve, substantially as described.
17. The combination, as hereinbefore set forth, with the turnable hinge-bar and the fixed hinge-sleeves mounted thereon and provided with the guide-braces formed with vertical slots, of the lazy-tong gate having the pivot-studs thereof working in the vertical slots of the guide-braces, the two sliding hinge-sleeves mounted on the hinge-bar and provided with lugs or projections, the brace-bar pivoted to the locking side of the gate, and the operating-lever hinged by its respective ends to the brace-bar and to the lug on the said uppermost hinge-sleeve, one cross-rod of the gate being pivoted to the lug on the sliding sleeve next below the uppermost sleeve, substantially as described.
18. The combination, as hereinbefore set forth, with the hinge-bar and the lazy-tong gate hinged thereto, of the upper sliding sleeve mounted on the hinge-bar and provided with guiding means and adapted to slide and turn on the bar, the said sleeve provided with a horizontal guide brace formed with a slot, the sleeve next below provided with guiding means and adapted to turn on the hinge-bar, but not to slide thereon, and formed with an upright arm, and the lever pivoted by one end to the said upright arm on the sleeve and having a fixed stud working in the slot of the said horizontal extension, said lever adapted to cover the heads of the cross-rods of the gate when the latter is extended, substantially as described.
19. The combination, as hereinbefore set forth, with the hinge-bar and the railing connected therewith, of the sliding and rotating hinge-sleeves mounted on the hinge-bar and provided with guiding means, the guide-braces on said sleeves, the lazy-tong gate having the cross-rods thereof pivoted to the guide-braces of the sleeves, a cut-away casing mounted on the hinge-bar, and a coil-spring encircling the bar under torsional tension, with one end fixed in the said casing and the other end fixed in the uppermost sleeve, substantially as described.
20. The combination, as hereinbefore set forth, with the hinge-bar and the sliding hinge-sleeves mounted thereon and provided with the horizontally-extending guide-braces or lugs, of the lazy-tong gate pivoted to the guide-braces, the vertical brace-bar pivoted to the locking side of the gate, and the operating-lever hinged between the brace-bar and the lug on the upper hinge-sleeve, the lever formed with a horizontal slot, and a pivot-stud on the gate working in such slot, substantially as described.
21. In a gate of the class described, the combination, as hereinbefore set forth, with the tubular hinge-bar formed with an upper and a lower transverse section, with the meeting faces of the sections formed irregular, so as to clutch, of a core for the sectional hinge-bar and a pin to prevent the upper section from rotating, but not from vertical movement, a lifting-stud for lifting the upper section out of contact with the lower section, so as to part the clutch-faces to allow the lower section to rotate, a longitudinal guide-rib on the lower section, and a sleeve having an L-shaped slot for engaging the lifting-stud, said sleeve provided with a groove for the guide-rib and sliding over the lower section, but not turning therein, the operating-lever hinged to said sleeve, substantially as and for the purpose herein described.
22. In a gate of the class described, the combination, as hereinbefore set forth, with the tubular hinge-bar comprising two transverse sections, the upper one of which is spring-acted and both having an irregular-formed clutch-like meeting face, of a core for the hinge-bar and a pin to prevent the rotation of the upper section, but not the vertical movement thereof, a lifting pin for lifting the upper section out of engagement with the lower section, so as to part the clutch-faces to allow the lower section to rotate, a longitudinal guide-rib on the lower section, and a sliding sleeve formed with an L-shaped slot for receiving the lifting pin and provided with a guide-groove for the guide-rib, the said sleeve sliding on the lower section, but prevented from turning thereon by the guide-rib, the operating-lever hinged to the said sleeve, substantially as described.
23. In a gate of the class described, the combination, as hereinbefore set forth, with the tubular hinge-bar comprising two transverse sections formed with clutch-like meeting faces, of a vertically-moving core for the hinge-bar, the upper section being fixed thereto, and a pin for preventing the core and upper section from turning, but not from moving vertically, a lifting-pin fixed to the core, and an L-shaped slot formed in the lower section to allow the pin to project through the section, a longitudinal guide-rib on the lower section, and a sliding sleeve mounted on the lower section and formed with an L-shaped slot to receive the said lifting-pin and provided with a guide-groove for the said guide-rib, the operating-lever hinged to the said sleeve, substantially as described.
24. The combination, with the pivoted cross-rods of a lazy-tong gate, of the transversely-divided brace-bar pivoted to the locking side of the gate for the purpose of spanning the hand-rail on the car, substantially as described.
25. The combination, with the hinge-bar and the lazy-tong gate, of the hinge-sleeves provided with the slots 32 and the guide-pins 33, the guide-braces 34, and the pivot-studs 30, attached thereto, substantially as described.

26. The combination, with the hinge-bar 22 and the lazy-tong gate 28, of the hinge-sleeves 31, provided with the slots 32 and the guide-pins 33, working in such slots, the guide-braces 34, provided with the slots 35, and the pivot-studs 30, working in the said slots and pivoted to the solid part of the guide-braces, substantially as described.
27. The combination, with the hinge-bar 22 and the lazy-tong gate 28, of the sliding hinge-sleeves 31, provided with the guiding means, the guide-braces 34, secured to the said sleeves, and the pivot-studs 30, attached to the braces, the collar 49, fixed to the hinge-bar, and the coil-spring 48, secured by its respective ends to the collar 49 and the adjacent hinge-sleeve 31, the casing 51, attached to the collar, substantially as and for the purpose herein described.
28. The combination, with the hinge-bar 22 and the lazy-tong gate 28, of the sliding hinge-sleeves 31, provided with the guiding means, the guide-braces 34, and the pivot-studs 30, connected therewith, the upper hinge-sleeve, 31, and the brace-bar 39 40, and the operating-lever 43, hinged between the head of the brace-bar and the guide-brace on the upper hinge-sleeve, substantially as described.
29. The combination, with the hinge-bar 22 and the upper sliding hinge-sleeve, 31, mounted thereon and provided with the guide-brace 34, of the vertical brace-bar 39 40, and the operating-lever 43, hinged to the brace-bar, and the boit 44, hinging the lever to the brace 43 and the knob 45 on the bolt, substantially as described.
30. The combination, with the hinge-bar 22 and the lazy-tong gate 28, of the sliding hinge-sleeves 31, mounted on the hinge-bar and provided with the guide-braces 34, the pivot-studs 30, connected with the braces, the said sleeves formed with the guide-grooves 38, the guide-ribs 37, fixed upon the hinge-bar, substantially as described.
31. The combination, with the hinge-bar 22, formed with the sockets 57 and 58, of the upper hinge-sleeve, 31, provided with set-screw 54 and formed with the projection 34, and the operating-lever 43, pivoted to the projection 34, substantially as described.
32. The combination, with the hinge-bar 22 and the lazy-tong gate 28, of the sliding hinge-sleeves 31, provided with the guide-braces 34, the pivot-studs 30, connected to the braces 34, the collars 36, fixed to the hinge-bar for limiting the downward movement of the sleeves, substantially as described.
33. The combination, with the turnable hinge-bar 22 and the lazy-tong gate 28, of the two upper sliding hinge-sleeves, 31, and the operating-lever 43, hinged to the topmost sleeve, and the cross-rod 29 of the gate pivoted to the adjacent sleeve 31, the fixed hinge-sleeves 31, provided with the guide-braces 34, formed with the vertical slots 35, the pivot-studs 30 of the gate working in the said slots 35, substantially as described.
34. The combination, with the hinge-bar 22, of the uppermost hinge sleeve, 31, provided with guiding means and having the guide-brace 34, formed with slot 35, the subjacent sleeve 31, formed with slot 32, and the pin 33 for such slot, and the upright arm 63 on the latter sleeve 31, the lever 43, pivoted to the upright arm 63, and provided with the stud 62, working in the slot 35 of the guide-brace, substantially as described.
35. The combination, with the tubular upper and lower sections, 64 and 69, provided, respectively, with the clutch-faces 65 and 70, of the core 68 and the stem 72 and the casing 73, the guide-slot 66 and the guide-pin 67 working therein, the lifting-pin 74, and the slotted sleeve 31, provided with guiding means and engaging with its slot the lifting-pin 74, substantially as described.
36. The combination, with the upper section, 64, and the lower section, 69, provided with the clutch-faces 65 and 70, respectively, of the core 68, and the stem 72 for supporting the core, the spring 71 and the casing 73, the guide-slot 66, formed in the upper section, 64, and the guide-pin 67, fixed to the core, the lifting-pin 74, fixed to the lower section, 69, and the sliding sleeve 31, provided with the L-shaped slot 32 for engaging with pin 74, the said sleeve provided with guiding means, substantially as and for the purpose herein described.
37. The combination, with the hinge-bar 22, the sliding hinge-sleeves 31, mounted thereon and provided with the guide-braces 34, the lazy-tong gate 28, pivoted to said guide-braces, of the forked operating-lever 43, provided with the slot 77 and hinged to the gate and to the forked guide-brace 34 of the uppermost hinge-sleeve 31, substantially as described.

In witness whereof we have hereunto set our hands.

JOHN B. GOODWIN.
GEORGE GOODWIN.
